DESIGN FOR A FLOWER HOLDER

Lewis P. Weil, Oak Lane, Pa.

Application September 4, 1935, Serial No. 58,428

Term of patent 7 years

To all whom it may concern:

Be it known that I, Lewis P. Weil, a citizen of the United States, residing in Oak Lane, in the county of Montgomery, State of Pennsylvania, have invented a new, original, and ornamental Design for a Flower Holder, of which the following is a specification, reference being had to the accompanying drawing, forming part thereof.

Fig. 1 is a front elevation of a flower holder showing my new design.

Fig. 2 is a plan view of the same.

I claim:—

The ornamental design for a flower holder as shown.

LEWIS P. WEIL.
